(57) CLAIM

The ornamental design for a proppant vessel base, as shown and described.

DESCRIPTION

FIG. 1 is an upper perspective view of the proppant vessel base showing *an embodiment of our design* [ ];

FIG. 2 is a front [elevation] *elevational view* [thereof] of the embodiment of FIG. 1;

FIG. 3 is a rear [elevation] *elevational view* [thereof] of the embodiment of FIG. 1;

FIG. 4 is a right side [elevation] *elevational view* [thereof] of the embodiment of FIG. 1;

FIG. 5 is [an opposite] a left side [elevation] *elevational view* [thereof] of the embodiment of FIG. 1;

FIG. 6 is a top plan view [thereof] of the embodiment of FIG. 1; and,

FIG. 7 is a bottom plan view [thereof] of the embodiment of FIG. 1.

[The features presented in broken lines are for environmental purposes only and form no part of the claimed design] *The broken lines depict portions of the proppant vessel in which the design is embodies that are not considered part of the claimed design.*

1 Claim, 2 Drawing Sheets

Matter enclosed in heavy brackets [ ] appears in the original patent but forms no part of this reissue; matter printed in italics indicates the additions made by reissue.
